Inventor:
Earl D. Brown,

By E. C. Troonan, Jr.,
his Attorney.

UNITED STATES PATENT OFFICE.

EARL D. BROWN, OF BAKERSFIELD, CALIFORNIA.

FRICITIONLESS SPRING.

1,387,041.

Specification of Letters Patent.

Patented Aug. 9, 1921.

Application filed January 29, 1921. Serial No. 440,928.

To all whom it may concern:

Be it known that I, EARL D. BROWN, a citizen of the United States, residing at Bakersfield, in the county of Kern and State 5 of California, have invented certain new and useful Improvements in Frictionless Springs, of which the following is a specification, reference being had therein to the accompanying drawings.

10 This invention relates to improvements in springs, and the object of the invention is the construction of a frictionless spring which is of such peculiar construction as will enable the leaves to be efficiently lubri- 15 cated.

Another object of the invention is the construction of a spring which has its leaves so constructed as to receive rollers between each two leaves, and which roller construction is 20 of such peculiar nature as will enable the operator to easily lubricate the leaves.

With these and other objects in view, my invention comprises certain novel combinations, constructions and arrangements of 25 parts as will be hereinafter described, illustrated in the accompanying drawings, and more particularly pointed out in the appended claim.

In the drawings:

30 Figure 1 is a fragmentary view, in elevation of a spring constructed in accordance with the present invention.

Fig. 2 is a fragmentary, enlarged view, in side elevation, of a portion of the spring.

35 Fig. 3 is a section, taken on line 3—3, Fig. 2, and looking in the direction of the arrows.

Fig. 4 is a fragmentary, inverted, perspective view of one of the leaves.

40 Referring to the drawings by numerals, 1 designates the top leaf, and 2 the bottom leaf of the spring. 3 are the intermediate leaves, and clip 4 holds all of the leaves together. In the under face of each intermediate leaf 3 and near its outer end is formed a recess 5, which recess is provided with an outer, vertical wall 6 and an inner, comparatively long, beveled wall 7. A roller 8 is seated in the recess 5, this roller being

provided with flat ends that bear against the 50 side edges of the leaves. The roller is prevented, by the vertical wall 6, from moving too far outwardly, but by reason of the beveled wall 7, the roller may move toward the central portion of the spring, thereby 55 further wedging or crowding contiguous leaves apart to allow the easy insertion of a lubricant or graphite between the leaves. Further, the device offers a working spring for lighter loads, as weight will be carried 60 mainly on the frictionless rollers 8, while added weight will bend the spring to a seat on the leaf below it, which can be kept well lubricated by means of the recesses in which the rollers work, offering abundant opportunity 65 for the introduction of greases and oils.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations 75 or changes as shall fairly fall within the scope of the appended claim.

What I claim is:

In a spring of the class described, the combination of a top and a bottom leaf, intermediate leaves interposed between the top and bottom leaf, each intermediate leaf provided in its under face and near its end with a recess open at both ends, said recess provided with an outer, vertical wall and an 80 inner, comparatively long, beveled wall, a roller in each recess being prevented from moving too far outwardly by the vertical wall and being permitted to move inwardly over the beveled wall to cause the contiguous 85 leaves to be spread apart, and said rollers provided with flattened ends bearing against the side edges of the leaves, substantially as shown and described.

In testimony whereof I hereunto affix my 95 signature.

EARL D. BROWN.
